RADIO RECEIVING SYSTEM

Filed July 22, 1926

FIG. 2

UNITED STATES PATENT OFFICE.

REUBEN ROSS, OF BROOKLYN, NEW YORK.

RADIO RECEIVING SYSTEM.

Application filed July 22, 1926. Serial No. 124,153.

This invention relates to radio receiving systems, and more particularly to systems having both radio and audio stages of amplification and employing electron discharge tubes as the amplifying means in such stages.

The object of the invention generally is to provide an improved device of the character described, which is effective, economical and readily manufactured.

10 More particularly an object is to provide a radio receiving system of the modern type having both radio and audio stages of amplification which gives substantially distortionless reception.

15 Other objects of the invention will in part be obvious and will in part appear hereinafter.

The invention accordingly comprises the features of construction, combinations of elements, and arrangement of parts, which will be exemplified in the constructions herein-after set forth and the scope of the application of which will be indicated in the claims.

For a fuller understanding of the nature 25 and objects of the invention reference should be had to the following detailed description taken in connection with the accompanying drawings, in which:

Figure 1 shows, diagrammatically, a radio 30 receiving system constructed in accordance with the present invention, and utilizing standard parts; and

Fig. 2 shows, in similar fashion, a radio system like that in Fig. 1 but arranged to 35 utilize tubes and audio transformers which are especially adapted to the present invention.

Referring now to the drawing, and first to Fig. 1, a receiving system is shown having 40 an aerial 10 connected through winding 11 to ground 12 for picking up the energy of the radio signal in the usual manner. The energy thus picked up is here shown as amplified by means of one radio stage, a detecting stage and two stages of audio; each stage 45 preferably employs an electron discharge tube as the amplifying means, or detecting means, as the case may be.

An electron discharge tube of the two or 50 three-element variety, as is well known, has unilateral conductivity, so that when connected in a circuit traversed by alternating currents, such a tube operates like a rectifier to cut off one-half of the alternating 55 current wave. Radio systems prior to my invention have been substantially universal.

ly actuated by half-wave pulses transmitted as a result of amplification by means of devices which have rectified current characteristics. The utilization of only the half of 60 the alternating current wave is not only the source of much inefficiency in the reception of radio signals in modern receiving systems, but also has been ascertained to be the source of much of the distortion in the 65 reproduction of signals.

In the practice of the present invention this source of distortion is substantially eliminated. This is accomplished by an arrangement of tubes adapted to transmit the 70 full wave, although through a divided circuit because of the inherent unilateral conductivity of the elements when functioning in an electron discharge tube.

In the drawing, this is shown as accomplished by coupling to winding 11 a secondary which is split or divided into two parts 13 and 13'. These two winding parts have a common tap 14 leading to one filament electrode 15 of a pair of parallel connected three-element tubes 16 and 16'. These tubes have their grid electrodes 17 and 17' respectively connected to the other ends of windings 13 and 13'. The plate electrodes 18 and 18' are also connected in parallel to 80 the end terminals of a winding 20 of a radio transformer which is also in two parts, the winding parts having a common tap or mid-point conductor 19 adapted to be connected to a "B-battery" source of relatively 85 high voltage DC. The source as here indicated is a pair of bus-bars 21-22, properly energized. Conductor 19 is shown as connected to bus-bar 21 for this purpose. There is also shown as associated with these bus-bars a third-bus-bar, designated 23; these 90 three comprise a means serving as the common source of high and low voltage electric energy for the system here illustrated. The bus-bars 22-23, which are connected to supply the current for heating all the filaments, 95 may, in like manner, be referred to as an "A-battery" source.

The windings 13 and 13' are connected in series with a variable condenser 24, in parallel with the tubes 16 and 16', which provides a tuned oscillating circuit by which the signal to be received may be selected.

The detecting stage is inductively coupled 105 to the first stage by means of the radio transformer 20, the secondary 25, of which is divided into parts similar to the primary and

connected respectively to the grid-electrodes 27 and 27' of the tubes 26 and 26', which tubes are here depicted as detectors. Resistance elements 28 and 28' are shown as connected across the grids and filaments of these tubes, but any convenient means adapted to maintain the desired potential across these tube-elements may be employed.

The plate electrodes of the tubes 26 and 26' are connected in parallel to one terminal of the primary 31 of an audio transformer 30 in order that one of the half-wave trains may be reversed and impressed on the audio stage; transformer 30, as shown, has a divided or split secondary 32; the end terminals of winding 32 are connected to the grid electrodes 37 and 37' of the tubes 36 and 36', while the mid-terminal 35 of this secondary is connected to one side of the filament bus-bars.

The plate electrodes of tubes 36 and 36' are connected through parallel circuits with what is in effect a second audio transformer 40 having split windings by which the second stage of audio amplification is produced; this second stage of audio amplification also has tubes 46 and 46' connected in parallel as in the prior stages. The plate electrodes of these last tubes are again connected to the windings of what is in effect an audio transformer 50 having split windings, a secondary of which is connected for energizing a translating device 60 such as telephones or a loud speaker.

By the arrangement shown, it is seen that the half wave transmitted by one tube in each stage is balanced by that transmitted by the other tube. There is no instant when a stage ceases to function and transmit signal energy; consequently in the audio stages the magnetization of the audio transformers is substantially always balanced. In the transformers at 30, 40 and 50 this balanced effect insures that the iron of the magnetic core is at no time free from magnetization. This effect is enhanced in the transformer at 30 by the use of one having a single primary and two secondaries on the one core. The effect of one transformer having split windings however, may be had by the use of two transformers connected as shown at 40. In this arrangement it is preferable to have the cores substantially abutting, so that there is natural magnetic linkage; a similar arrangement is shown at 50.

Since the cores here in the audio stages are substantially always magnetized, the harmonics due to the intermittent magnetization of cores by the current heretofore unilaterally transmitted from a single series of tubes, is absent, together with diminution by hysteretic losses. The reproduction of the signal received in the translating device 60 has in consequence great strength and is substantially free from distortion.

In order that the energy traversing the parallel sides of the respective stages in the arrangement shown in Fig. 1 may give a fully balanced effect, the currents in the two sides should be as nearly equal as practical and in phase. Consequently care is taken that the inductance in the two sides of the circuits in each stage has as nearly equal values as practical. Care should also be taken to avoid having these circuits at any point intercepted by leakage flux; shielding may therefore be resorted to with advantage.

An arrangement is shown in Fig. 2 in which special parts are employed. Here the aerial 10 is connected through winding 11 to ground 12. The end terminals of the divided secondary, coupled to winding 11, however are here not connected to the grid electrodes or parallel connected three-element tubes, but instead are connected in parallel respectively to the two grid-electrodes 77 and 77' of a single special five-element tube 76.

The five-element tube here illustrated has one filament, two grid-electrodes and two plate-electrodes. The latter are shown at 78 and 78' and have parallel connections leading to the opposite terminals of a divided primary of a radio transformer at 80, which couples the first radio stage to the detecting stage; the latter having a five-element detecting tube 86 connected similar to that at 76. The plate electrodes of tube 86 are connected in parallel to an end terminal of an audio transformer 90 having a divided primary and secondary, the primary sections being connected in parallel and arranged to increase the magnetizing effect. The balanced effect in this case is enhanced by providing one transformer having a common iron core in the two sides of the circuit. In this way the magnetization of the core is substantially always present and is substantially uniformly distributed throughout the core.

Two stages of audio, using the five-element tubes shown at 96 and 106, are coupled successively thereto. Due however to the balanced transmission of the signal in the audio stages here employed, three or more stages of audio may be employed equally well. A translating device 120 is coupled to the last stage of audio through the audio transformer 110 which is also shown as having a common iron core for the parallel sides of the circuit which lead from the plate-electrodes of the last audio stage. A common source of filament heating current for the special electron discharge tubes is here shown at 83, but as it is frequently preferable in multi-stage receiving systems to use various voltages in the plate circuits, the stages are here shown as provided with individual sources of current-energy for plate circuits. It will be understood however that this is a mere symbolic showing and that

any convenient arrangement for supplying selected plate voltages from one or more sources is within the purview of the present invention.

5 The arrangement shown in Fig. 2 differs essentially from that shown in Fig. 1 only in the use of the special five-element tubes and in the use of the specially wound audio transformers which latter have common 10 cores for the divided windings. By the arrangements shown in Fig. 2 the present invention is practiced in a highly efficient form but it is seen that the use of transmitted balanced half waves united in the audio 15 stages and in the translating device to give a full wave effect characterize the arrangements of each.

Since certain changes may be made in the above construction and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent, is:

1. In a radio receiving system, the combination with receiving means, of amplifying stages connected in cascade therewith having amplifying means with rectifying characteristics connected therein and arranged to provide parallel paths for unilaterally conducting each of the half-wave trains of the full-wave signal, an intermediate stage thereof being arranged as a detecting stage, means for reversing one of said half-wave trains associated 30 with said detecting stage, said reversing means being arranged for transmitting the reversed wave train additively with the unreversed train in parallel paths through the succeeding cascade stages, and 35 a translating device connected to the last stage whereby the same is energized continuously by said additive parallel wave trains.

2. In a radio receiving system, the combination with receiving means, of amplifying 50 stages connected in cascade therewith having electron discharge tubes connected therein and arranged to provide parallel paths for unilaterally conducting each of the half-wave trains of the full-wave signal, an intermediate stage thereof being arranged as 55 a detecting stage, means for reversing one

of said half-wave trains associated with said detecting stage, said reversing means being arranged for transmitting the reversed wave train additively with the unreversed train 60 in parallel paths through the succeeding cascade stages, and a translating device connected to the last stage whereby the same is energized continuously by said additive parallel wave trains. 65

3. In a radio receiving system, the combination with signal receiving means, of amplifying stages connected in cascade therewith, including a detecting stage, and a subsequent audio stage, each of said stages having amplifying means with a rectifying characteristic connected therein and arranged to provide parallel paths for unilaterally conducting each of the half-wave trains of the full-wave signal, a transformer 70 associated with said detecting stage and arranged to comprise the coupling between said detecting stage and the subsequent audio stage, said transformer having a winding for reversing one of the half-wave trains from 75 said detecting stage, said audio stage having inductive coupling means provided with windings divided between said parallel paths and with effective common magnetic coupling means, and a translating device 80 inductively coupled to said cascaded stages whereby the same is continuously energized with full-wave energy. 85

4. In a radio receiving system, the combination with signal receiving means, of amplifying stages connected in cascade therewith including a detecting stage and a subsequent audio stage, each of said stages having three-electrode-electron discharge tubes connected 90 therein and arranged to provide parallel 95 paths for unilaterally conducting each of the half-wave trains of the full-wave signal, a transformer associated with said detecting stage and arranged to comprise the coupling between said detecting stage and the subsequent 100 audio stage, said transformer having a winding for reversing one of the half-wave trains from said detecting stage, said audio stage having inductive coupling 105 means provided with windings divided between said parallel paths and with effective common magnetic coupling means, and a translating device inductively coupled to said cascaded stages whereby the same is continuously energized with full-wave energy. 110

In testimony whereof I affix my signature.
REUBEN ROSS.
